APPARATUS FOR ENRICHING AIR

Jesse G. M. Bullowa, New York, and Herman D. Ratish, Brooklyn, N. Y.

Application May 23, 1939, Serial No. 275,211

16 Claims. (Cl. 128—191)

This invention relates to apparatus for evaporating liquid oxygen and supplying the vapor to the surrounding air for the purpose of enriching the oxygen content of the air in a truck airplane, or other vehicle, or any cabin or enclosure where such added oxygen is desirable for breathing.

It is an object of this invention to provide improved apparatus for producing oxygen vapor by the evaporation of liquid oxygen. More specifically, an object of the invention is to obtain improved control of the rate of evaporation and volume of oxygen vapor supplied by the apparatus.

One feature of the invention relates to variation in the surface area of the liquid for controlling the rate of evaporation, and the preferred embodiment of the invention includes, in combination with the surface variation, a control of the volume of air that passes into contact with the liquid surface.

Another object of the invention is to provide oxygen evaporating apparatus of simple and inexpensive construction which can be tipped or even inverted without spilling any of the liquid contents.

Other objects, features and advantages of the invention will appear or be pointed out as the specification proceeds.

The drawing is a vertical sectional view through an oxygen evaporator embodying the invention, with the auxiliary equipment shown diagrammatically.

A spherical vessel 8 comprising an outer shell 9, and inner shell 10, has necks 11 and 12 at the upper and lower poles, respectively, of the outer shell. The vessel is supported for rotation about its polar axis by a bearing 14 that surrounds the upper neck 11, and a frusto-conical bearing 15 on which the lower neck 12 rests. The bearings 14 and 15 are carried by brackets 17 and 18, respectively, and these brackets are connected to a wall or bulkhead 19.

The shells 9 and 10 are preferably metal, and there is a thick layer of heat insulating material 20 between these shells to prevent any substantial quantity of heat from reaching the interior of the vessel and causing evaporation of the liquid oxygen when the apparatus is not in use.

An air inlet 21 in the inner shell is in alignment with a passageway 22 in the upper neck 11 of the vessel. Air and oxygen vapor flow from the vessel through a discharge pipe or tubing 23, which includes a spiral section surrounding the outside shell 9. The spiral tubing 23 is made of metal and is a good conductor of heat. The lower end of

the tubing 23 is near enough to the bottom of the vessel 8 to be above the level of the liquid oxygen when the vessel is inverted. The tubing 23 has a flaring end 24.

5 The liquid oxygen in the spherical vessel is indicated by the reference character 25. The liquid is initially poured into the vessel through a filling port 26. The vaporization and delivery of the oxygen is at substantially atmospheric pressure, 10 and the delivery pipe or tubing 23 is at all times open to the atmosphere; but the vessel 8 has a relief valve 27 for protection in case the tubing 23 is obstructed or mashed so that vapor can no longer escape through the delivery tubing as rapidly as the vapor is evolved in the vessel 8.

A swing check-valve 30 is hinged to the inner shell 9 adjacent the inner end of the air inlet 21 in position to close and block the outflow of liquid oxygen in the event that the vessel becomes inverted, as sometimes occurs in airplane use when the airplane flies through a vertical loop.

20 Air is supplied to the vessel 8 by a blower 32 driven by an electric motor 33. A pipe 34 leads from the delivery outlet of the blower 32 to a stuffing-box 35 into which the upper end of the neck 11 extends. The reduced upper end of the neck 11 is free to rotate in the stuffing-box 35 but the packing prevents air from escaping around the outside of the neck 11 and causes the air from the pipe 34 to flow through the passageway 22 and into the spherical vessel 8. The supply of air from the blower can be controlled by a valve or damper 36 in the pipe 34.

25 The spherical vessel 8 is rotated by a driving shaft 38 that turns in a bearing in the end of the bracket 18, which bearing is coaxial with the frusto-conical bearing 15. The shaft 38 is connected with an electric motor 39 through motion transmitting means, shown in the drawing as a flexible shaft 40 and reduction gearing 41. The speed of the motor 39 is controlled by a rheostat 42 and switch 43, both of which are preferably located on a dash-board 44 when the apparatus is installed in an airplane, truck or other vehicle.

40 In the operation of the apparatus, air is supplied through the passageway 22 by the blower 32, and the rate of air flow is controlled by the valve or damper 36. When the spherical vessel 8 is stationary, the surface of the liquid oxygen is level, but when the vessel is rotated about its substantially vertical axis, the surface of the liquid becomes concave and increases in area.

45 As the speed of rotation of the spherical vessel increases, the concavity of the liquid surface increases, with resulting increase in surface area.

If the speed of rotation is carried high enough, all of the liquid oxygen will be held against the sides of the vessel by centrifugal force so that the body of oxygen is in the form of an annulus.

The tubing 23 forms a right-hand spiral around the vessel 8, and the vessel is preferably rotated to the right (as viewed from the top). When the axis of rotation is at a substantial angle to the vertical, any liquid that splashes into the discharge pipe 23 will tend to drain back into the vessel 8 with the vessel and spiral rotating in this direction. The rotation of the spherical vessel causes agitation of the liquid oxygen, especially when the axis of rotation is on a slope. This agitation generates heat and further increases the area of contact with the air; and both of these phenomena promote ebullition of the liquid oxygen.

One embodiment of this invention has been illustrated and described, but changes and modifications may be made without departing from the invention as defined in the claims.

We claim:

1. A liquid oxygen vaporizer comprising a container, bearings supporting said container for rotation about a substantially vertical axis, means for rotating the container about said axis to augment the rate of evaporation of the liquid oxygen within the container, and a gas delivery outlet through which gas is supplied from the container while rotating about said vertical axis.

2. A vaporizer for liquid oxygen including a vessel for enclosing a quantity of liquid oxygen, heat insulating material around the vessel for preventing substantial heat flow into the vessel when the vaporizer is not in use, bearings on which the vessel is rotatably supported, and means for imparting a continuing rotation to said vessel to stimulate evaporation of the liquid oxygen.

3. A liquid oxygen evaporator comprising a closed vessel in which the liquid oxygen is contained, bearings in which the vessel is rotatable about an upwardly extending axis to increase the liquid oxygen surface exposed to the air, said vessel having a passage for the entrance of air, and an outlet through which air and oxygen vapor flow out of said vessel when the vessel is rotating about said upwardly extending axis, and apparatus for supplying a stream of air through said passage.

4. A liquid oxygen evaporator comprising a container for the oxygen, means for rotating the container to augment evaporation, and apparatus for controlling the speed of rotation to regulate the rate at which vapor is evolved.

5. A liquid oxygen vaporizer including a liquid container with separate conduits for the entrance of air and the discharge of the air-oxygen mixture, bearings in which the container is rotatable to increase the surface of liquid exposed to the air, a variable speed motor, motion transmitting connections through which the motor rotates the liquid container, and means for regulating the motor speed to control the surface area of the liquid oxygen.

6. Air enriching apparatus for a truck or airplane or other vehicle including in combination a liquid container with separate conduits for the entrance of air and the discharge of the air-oxygen mixture, bearings in which the container is rotatable to increase the surface of liquid exposed to the air, a variable speed motor, motion transmitting connections through which the motor rotates the liquid container, and motor

speed control means located on the dash-board of the vehicle within reach of the driver of the vehicle.

7. A vaporizer for liquid oxygen including a vessel for enclosing a quantity of liquid oxygen, heat insulating material around the vessel for preventing substantial heat flow into the vessel when the vaporizer is not in use, means including an electric motor for rotating the vessel to cause vaporizing of the liquid, and apparatus that regulates the motor speed to control the rate of vaporization of the liquid oxygen.

8. The combination of a container for liquid oxygen with separate conduits for the entrance of air and the discharge of the air-oxygen mixture, means including a motor for rotating the container to increase the surface area of the liquid oxygen, apparatus for supplying a current of air into the container and into contact with the surface of the liquid oxygen, and a device associated with the air supply apparatus for controlling the volume of air supplied to the container.

9. The combination of a container for liquid oxygen with separate conduits for the entrance of air and the discharge of the air-oxygen mixture, bearings in which the container is supported and rotatable about a substantially vertical axis, a variable-speed electric motor, motion transmitting connections through which the motor rotates the container to increase the surface area of the liquid oxygen, apparatus for supplying a current of air into the container and into contact with the surface of the liquid oxygen, and a valve or damper in the air supply apparatus for throttling the air supply to the liquid oxygen container.

10. An oxygen evaporator comprising a substantially spherical container with aligned necks at its top and bottom, an opening through one of the necks communicating with the interior of the container, and bearings in which the necks turn, said bearings being disposed to support the container for rotation about a substantially vertical axis.

11. In a liquid oxygen evaporator, a closed vessel in which the liquid oxygen is contained, necks at the top and bottom of said vessel, supporting bearings in which the necks rotate about a substantially vertical axis, and an air inlet for the vessel extending through one of said necks.

12. In a liquid oxygen evaporator, a closed vessel in which the liquid oxygen is contained, necks at the top and bottom of said vessel, supporting bearings in which the necks rotate about a substantially vertical axis, an air inlet opening into said vessel through the top neck, and means for rotating the vessel including a driving element operatively connected with the lower end of the bottom neck.

13. A liquid oxygen vaporizer comprising a container and bearings in which the vessel rotates, an air inlet passage extending axially through a member of the bearing and into the container and an outlet passage including a long length of metal tubing that passes around the outside of the vessel.

14. An air enriching apparatus comprising a closed vessel in which liquid oxygen is contained, an outlet for the discharge of oxygen vapor from the vessel, a substantial length of tubing attached to the vessel and leading from the outlet downward around the outside of the vessel in a spiral, bearings in which the vessel is rotatably supported, and means for rotating the vessel and

spiral in the direction that the oxygen moves around the vessel when passing through the convolutions of the tubing.

15. An air enriching apparatus comprising a closed vessel with separate conduits for the entrance of air and the discharge of the air-oxygen mixture, a heat insulating covering on the vessel, a filling plug which can be removed when additional liquid is to be poured into the vessel, a safety valve for the escape of excessive pressure, bearings supporting the vessel and in which said vessel is rotatable about a normally vertical axis, a variable speed motor, motion transmitting connections through which the motor rotates the vessel, remote control apparatus for regulating the motor speed, a motor-driven blower with a delivery pipe connected to the inlet conduit, valve means in the delivery conduit adjustable to regulate the rate at which air is blown into the vessel,

5 an outlet tubing of high heat conductivity and substantial length attached to the vessel over the insulating covering and extending in a spiral from the discharge conduit to a level near the bottom of the vessel, and a flaring exit on said outlet tubing.

10 15 16. An oxygen vaporizer, for enriching the atmosphere in an airplane cabin, including in combination a vessel in which liquid oxygen is contained, and an outlet pipe for the oxygen vapor, said outlet pipe being curved around the vessel so that a part of the outlet pipe is above the level of the liquid oxygen no matter which way or how much the vessel is tipped, the exhaust end of said outlet pipe being at a low level which is above the liquid level of the oxygen when the vessel is inverted.
